UNITED STATES PATENT OFFICE.

GEORGE B. KELLY, OF BOSTON, MASS., ASSIGNOR TO THE MECHANICAL ORGUEINETTE COMPANY, OF NEW YORK, N. Y.

PROCESS OF MANUFACTURING PERFORATED SHEETS FOR MECHANICAL MUSICAL INSTRUMENTS.

SPECIFICATION forming part of Letters Patent No. 223,675, dated January 20, 1880.

Application filed June 14, 1879.

To all whom it may concern:

Be it known that I, GEORGE B. KELLY, of Boston, in the county of Suffolk and State of Massachusetts, have invented a new and useful Process of Manufacturing Perforated Sheets for Mechanical Musical Instruments, of which the following is a specification.

My invention relates to the manufacture of perforated sheets of paper to be used in mechanical musical instruments as a means of controlling the passage of wind through the reeds, whereby the several tones are sounded in the proper order and of the desired duration to produce harmony; and it has for its object a reduction in the cost of such sheets by facilitating the cutting of the perforations.

Heretofore such sheets have been perforated while in a dry state by means of tubular cutting-punches of the form and size of the desired perforations and a mallet manipulated by hand, and in order to reduce the cost of the sheets to the minimum it is very desirable to punch a series of sheets at the same time; but this has been found impracticable when the sheets are dry, on account of the breaking of the punches, caused by the unyielding nature of the cores of paper cut out and forced into the punch, the interior of which is necessarily made tapering.

To obviate this difficulty I have conceived and practically carried into effect my improvements, which consist in wetting the strips of paper cut to a uniform width, placing a series of said wet strips in a pile, punching the several holes desired through the pile while in a wet or damp state, hanging said sheets in a hot chamber to dry until they have shrunk to a given width at which it is desired to arrest further contraction, and then placing said sheets between thin boards and subjecting them to a heavy pressure in a press or clamp, to prevent further contraction until they are completely dry, and to insure their drying in a flat or uncockled condition.

It being understood that it is necessary that the perforations in the strip of paper should be a distance apart in the direction of the width of the paper exactly corresponding to the positions of the several reeds, and that the

perforations are made when the paper is expanded by being wet, the necessity for arresting the contraction of the paper in the process of drying at just the right time will be apparent.

In carrying out my process, I pass the strips of paper in succession endwise through a bath of water and hang them up to drip till I have strips enough wet to form a pile, when the first strip wet is placed upon a table or bench with one of its edges against a gage, with all wrinkles smoothed out, and the remaining strips are placed in succession upon the first one in the order in which they were wet.

When the desired number of strips have been placed in the pile (usually about a dozen) the perforated pattern, which may be of sheet metal or thick straw-board, preferably the latter, is placed upon the pile, and the whole is removed from the table where the pile is made up and placed upon another table provided with means for clamping the whole together, which being done, the operator proceeds to punch the desired holes, using punches of different sizes, according to the size of the holes in the pattern.

When the holes are all punched the several strips in the pile are hung up in a hot room to dry, where they are occasionally inspected and their widths measured by the attendant, and as fast as the strips become contracted to the desired width they are removed from the dry-room and placed in a flat position in piles of four (more or less) between thin boards, and then placed in a press or clamp, where they are subjected to a heavy pressure for about twelve hours. They are then removed from the press, repiled, as before, between thin boards, care being taken to smooth out all irregularities, and they are again placed in the press and subjected a second time to the same heavy pressure for about the same length of time, when they are removed, and are found to be dry and ready to be used as single tunes or airs, or to be gummed together to form medleys.

What I claim as new, and desire to secure by Letters Patent of the United States, is—

The process herein set forth for preparing

perforated music-sheets from paper, which consists in wetting the strips or sheets of paper, placing a series of said sheets in a pile, punching through the several sheets of the pile at one operation while they are in a wet or damp state, drying them in a hot room till they have shrunk to a given width, and then subjecting them to a heavy pressure between flat plates

or boards till they are thoroughly dried, substantially as described.

Executed at Boston, Massachusetts, this 13th day of May, A. D. 1879.

GEO. B. KELLY.
